DRY-CLEANING MACHINE

Application filed April 1, 1929. Serial No. 351,769.

Our invention relates to machines for dry cleaning clothes and other articles of wearing apparel, and it has for a purpose the provision of a machine characterized by its ability to 5 clean articles of wearing apparel and the like effectively and rapidly, our invention being particularly adapted for cleaning, without injury thereto, delicate garments, such as lingerie, gloves, pocketbooks and other articles 10 of wearing apparel.

It is also a purpose of our invention to provide a dry cleaning machine which is characterized by the functional relationship of a movable body upon which the articles to be 15 cleaned are supported and adapted to be moved in the presence of a cleaning liquid to circulate the liquid around and through the articles, and a plurality of objects freely movable and adapted to be actuated under movement of the body to act on the articles to be 20 cleaned in a manner to augment circulation of the cleaning liquid, and to otherwise aid in cleaning the articles.

A further purpose of our invention is the 25 provision of a dry cleaning machine which embodies a casing removably fitted in a frame and adapted to contain a quantity of cleaning liquid, and a rotary drum rotatable in the casing and removable therefrom to permit 30 thorough cleaning of the drum and casing when required.

We will describe only one form of dry cleaning machine embodying our invention, and will then point out the novel features in 35 claims.

In the accompanying drawing:

Figure 1 is a view showing in side elevation one form of dry cleaning machine embodying 40 our invention with the upper section of the casing in open position;

Fig. 2 is a vertical sectional view taken on the line 2--2 of Fig. 1;

Fig. 3 is a vertical sectional view taken on the line 3--3 of Fig. 2;

Fig. 4 is a fragmentary sectional view taken on the line 4--4 of Fig. 2;

Fig. 5 is an enlarged fragmentary perspective view of one of the bearings for the drum 50 of the machine illustrating the manner in

which it is mounted in the form of the machine; and

Fig. 6 is a detail perspective view of one of the bearing blocks.

In carrying out our invention, we provide a 55 frame consisting of two end members each of which includes a pair of legs 15 secured detachably to a cross-plate 16, the plate being of substantial width, as illustrated in Fig. 1, and having bolted or otherwise secured there- 60 to a bar 17 which constitutes a bracket for supporting other parts of the machine. As illustrated in Fig. 5, the bar 17 is of angular form, and it is so secured to the plate 16 that one angular portion thereof projects outward- 65 at right angles from the plate and between the legs 15, as illustrated in Fig. 1. As further illustrated in Fig. 5, the vertical portion of the bar 17 and the outer portion of the plate 16 are cut away at corresponding points 70 to accommodate a block 18 having an opening 19 therethrough so as to provide a bearing for a shaft to be described hereinafter. As clearly illustrated in Fig. 6, this bearing 75 block 18 is flanged, as indicated at 20, to provide lips for confining the block against horizontal displacement from the frame, although the block may be removable vertically from the frame to allow removal of the shafts 80 which the two bearing blocks receive when it is desired to remove the drum upon which the shafts are fixed.

The frame is adapted to removably receive a casing including a lower section 21 and an upper section 22, the latter section being 85 hingedly connected, as indicated at 23, to the lower section so that it can be moved to occupy open or closed position. The two sections 21 and 22, when in closed position, cooperate to provide a casing of cylindrical form 90 in which a drum is adapted to be received.

As illustrated in Figs. 1, 2, and 5, the upper edges of the opposite ends of the lower section 21 of the casing are provided with L-shaped flanges 24 which, in the applied position of the casing section to the frame, are adapted to engage over the upper edges of the plate 16 of the frame in order to support the casing section as a unit on the frame. The manner in which one flange 24 engages the 100

corresponding plate 16 is best illustrated in Fig. 5, and wherein it will be seen that the flange is cut away at a point corresponding to the cut-away portions of the plate and bar to accommodate the corresponding bearing block 18.

From the preceding description, it will be manifest that by providing a casing section 21 with the two end flanges constructed and 10 applied as described, the casing section as a whole is suspended within the frame, and in a manner to allow the ready removal thereof from the frame when desired, in order that the casing as a whole may be disassociated 15 with respect to the frame members to facilitate disassembling of the entire machine incident to storage or shipment.

The machine also includes a drum generally indicated at D, and which is adapted to 20 be housed within the casing when the two sections of the latter are in closed position. This drum D is illustrated in Figs. 2 and 3, as comprising end heads 25 of disk form connected by a circular series of slats 26. The slats are 25 slightly spaced to provide restricted intervening slots 27 through which the cleaning fluid contained in the lower casing section may enter the drum. The inner surfaces of the slats 26 are transversely corrugated, as indicated 30 at 28, in order to provide surface protuberances on the inner periphery of the drum, which function in a manner to be described hereinafter. The drum is provided with an opening through which articles to be cleaned, 35 or have been cleaned, may be inserted or removed, and this opening is controlled by a door 29 which constitutes a part of the peripheral portion of the drum, and is constructed by sectioning certain of the slats 26 40 and connecting the movable sections of the slats by the leaves of a pair of hinges 30 of the piano type. On a stationary part of the drum are mounted a pair of spring-pressed latches 31 normally engaging the projecting 45 ends of the hinges and manually movable to disengage such ends to permit movement of the door to open position.

To mount the drum D for rotative movement within the casing of the machine, we 50 provide a pair of cleats 32 (Fig. 2), secured to the outer faces of the heads 25 so as to extend diametrically thereof, and with their medial portions provided with hubs in one of which is secured a stub axle 33, and in the other a 55 shaft 34. The two shafts are journaled in the bearing blocks 18, with the shaft 34 of such length as to project from the bearing and the plate 16 of the adjacent frame in order that it may be operatively connected to a 60 source of power (not shown), or provided with a crank (not shown), by which the drum may be manually rotated. Thus, the drum is supported by the shafts for rotative movement within the casing, and when the 65 upper section of the casing is in closed posi-

tion as illustrated in Fig. 2 it provides a closed housing for the drum. In practice, the lower casing section 21 is adapted to contain a suitable cleaning liquid which seeks its own level in the drum by entering the latter through the slots 27 as has been described.

For the purpose of augmenting circulation of the cleaning liquid in the drum in respect to the articles to be cleaned contained in the drum, and to otherwise promote the rapid and thorough cleaning of the articles, we provide a multiplicity of objects such as the balls 35 (Fig. 3). These balls are formed preferably of wood, and of a weight sufficient to produce the desired motions in respect to the articles 80 to be cleaned when and under rotative movement of the drum.

The operation of the machine is as follows:

With the articles to be cleaned positioned in the bottom of the drum, as illustrated in Fig. 3, and so as to be submerged in the cleaning liquid, and the balls 35 in position on top of the articles, let it be assumed that the drum is rotated in a clockwise direction as indicated by the arrow. Under such movement, the slats by reason of their corrugations and slight spacing operate to lift the cleaning liquid until gravity acts to return the liquid to the bottom of the drum. In its return, liquid precipitates onto the articles, thus producing what may be termed a rinsing action that serves to greatly aid in removing the dirt from the articles. The balls 35 constantly roll on the surface of the articles producing a gentle rubbing and depressing action on the articles to further circulate the cleaning liquid around and through the articles. Of course, the articles themselves are elevated in the drum by reason of the rising corrugated slats, but they are not elevated to any appreciable degree before gravity acts to return them to the bottom of the drum so that the balls which tend to move with the liquid are caused to roll on the surface of the articles. The restricted or relatively narrow slots 27 between the slats restrict drainage of the cleaning liquid back into the casing and thus at all times retains in the drum a quantity of liquid sufficient to be elevated by the corrugations of the slats and finally precipitated onto the articles to produce the previously described rinsing action. This action of the cleaning liquid combined with the circulating and rubbing action of the balls produces a rapid and effective cleaning of the articles that does not operate to unduly wear or otherwise injure the articles being cleaned, and by reason of these virtues the machine has been found to be particularly useful in the rapid and thorough 110 cleaning of extremely delicate garments and 115 gloves.

Should it be desired to clean the drum and the interior of the casing, the drum can be 120 readily removed from the casing and the cas- 130

ing from the frame, as will be manifest from a consideration of the preceding description of the construction and association of the parts enumerated.

5 Although we have herein shown and described only one form of dry cleaning machine embodying our invention, it is to be understood that various changes and modifications may be made herein without departing from the spirit of the invention and the 10 spirit and scope of the appended claims.

We claim:

1. In a machine of the character described, a frame having cross members, bearings in 15 the cross members, a casing having a lower section and an upper section movable on the lower section to open and close, extensions on the lower section engaging the cross members for supporting the lower section within the 20 frame, and a drum having shafts engaging within the bearings for supporting the drum for rotative movement within the casing.

2. In a machine of the character described, a frame, bearing members removably fitted 25 in the frame, a casing having a lower section and an upper section movable on the lower section to open and close, extensions on the lower section engageable with the frame for suspending the lower section within the 30 frame, and a drum having shafts engaging within the bearings for supporting the drum for rotative movement within the casing.

3. In a machine of the character described, a frame having end plates, angle bars secured 35 to the plates, said plates and bars having openings therein, bearing blocks disposed within the openings of said bars and plates, a casing having a lower section and an upper section movable on the lower section to open 40 and close, flanges on the lower section engaging said plates for suspending the lower section within the frame, said flanges having cutaway portions to accommodate said bearing blocks, and a drum having shafts engaging 45 within the bearing blocks for supporting the drum for rotative movement within the casing.

ONÉSIME THIBAULT.
